(57) **CLAIM**

The ornamental design for a catheter with variable funnel shape, as shown and described.

DESCRIPTION

FIG. 1 is a perspective view of a catheter with variable funnel shape, showing a an embodiment of the new design with the ridges on the catheter funnel shown in broken lines. FIG. 2 is a right side elevational view of the catheter with variable funnel shape of FIG. 1.

FIG. 3 is a left side elevational view of the catheter with variable funnel shape of FIG. 1.

FIG. 4 is a rear elevational view of the catheter with variable funnel shape of FIG. 1.

FIG. 5 is a front elevational view of the catheter with variable funnel shape of FIG. 1.

FIG. 6 is a top plan view of the catheter with variable funnel shape of FIG. 1; and,

FIG. 7 is a bottom plan view of the catheter with variable funnel shape of FIG. 1.

The broken lines in the drawings show certain environmental structure and form no part of the claimed design.

1 Claim, 3 Drawing Sheets
